UNITED STATES PATENT OFFICE.

LOUIS E. DELSON, OF CHICAGO, ILLINOIS.

ILLUSTRATED LETTERHEAD.

Application filed September 14, 1925. Serial No. 56,375.

My invention relates to commercial stationery, advertising folders or broadsides, particularly to letterheads.

The objects of my invention are to provide a letterhead adapted to carry, in addition to the usual name and address and the text matter of a letter, a display advertisement or printed reproduction. This would provide a space measuring approximately 10 8" x 17" to carry the advertisement of goods offered by the merchant or advertiser, such display advertisement being of pictorial character of fixed form, such as that standardized by him in obtaining publicity for 15 his products, but which pictorial display shall not trespass upon the portion of the letterhead reserved for the usual name and address at the top of a letterhead, and in conjunction therewith to provide a letterhead in usual form adapted to be varied so as to be usable by agents in different localities, whose names and addresses may be printed thereon, a separate letterhead imprint being provided for each agent, as well 20 as for the advertiser in his own use of this illustrated letterhead. The foregoing and other objects of my invention will appear from the following specification and the drawings accompanying same. In the drawings forming part of this specification, Figure 1 is a plan view of the illustrated letterhead adapted to be folded upon the dotted line A A; Figure 2 is a like view of the sheet when folded; and Figure 3 is a 25 back view of the sheet unfolded. In these drawings, 1 is the body of the illustrated letter, size approximately 8" x 8½", adapted to receive the written contents of the letter, to be folded upon the dotted line A A, and 2 is the standard printing surface, measuring approximately 16" x 8", and 3 is the individual letterhead, measuring approximately 3" x 8" adapted to be folded as to 30 caption.

In carrying out my invention, I provide an illustrated letterhead, preferably longer than the standard size of a letterhead, the standard size of a letterhead being approximately 8½" x 11". The preferred embodiment of my invention is an illustrated letterhead 19" long, the lower portion having a length of 8" being folded over on the body of the letterhead, thus leaving 3" visible for the usual letterhead. Upon this folded

over portion and that part of the letterhead 55 covered thereby there is displayed such printed matter, preferably in the form of a pictorial illustration or reproduction of an advertisement as may be adapted by the merchant as his standard or fixed form of 60 illustration for the goods, wares, merchandise or service dealt in by him. This form of display advertisement is preferably a one color or a colored print of copyrightable character, whose characteristics essentially 65 partake of those of a trade mark, in that it denotes the origin of the goods and is in such fixed invariable form as may be familiar to the public as identifying products of that maker, or an advertisement used to further 70 the sale of his merchandise, wares or services. The folded over portion of the letterhead normally conceals this advertisement. Upon this folded over portion is multi-graphed, typewritten or written the letter 75 or communication, together with the salutation and signature of the manufacturer or merchant or of the agent or dealer representing him in a given territory accompanied by a description of the goods dealt in 80 for advertiser.

These standard illustrated letterheads may be printed in quantities by the merchant and supplied by him to his agents. The stationery so supplied to each particular agent can also bear the imprint of the name of the manufacturer. When the name of the agent is imprinted instead, the stationery becomes the agent's individual letterhead by imprinting upon the upper part, 90 measuring approximately 8" x 3" caption with his name or the name under which he transacts business, together with his address and suitable date line. The stationery thus used by each agent in his business 95 correspondence bears his personal letterhead, together with the general display advertising matter of his principal.

The illustrated letterhead embodying my invention arouses, by its novelty, the interest of the recipient of the goods featured thereon, and upon his lowering the folded over letter serves to impress with a more vivid concept of the advertisement illustrated. My invention has special utilities 100 which enables the merchant to print letterheads in larger quantities and therefore at 105 less cost and considerable economy, partic-

ularly where color printing is used to supply quantities to each agent from stock, as required, without reprinting or waste of those otherwise printed if unused. By the absence of advertising matter from the letterhead as folded, the letter as received is in appearance of the usual commercial character, but upon lowering the folded over letter, the surprise and interest of the recipient is secured by the contrasting picture then displayed. The illustrated letterhead in its entirety constitutes a dignified and attractive innovation for commercial stationery, for general form letter use and for use as illustrated letterheads.

It will be understood that various changes in the forms and preparations of my illustrated letterhead may be made without departure from the appearance of my invention or sacrifice of any of its advantages, as, for example, the sheet need not be of standard commercial size but may be of irregular size or form, since folded over portion may be any part thereof, which can be suitably used for the letter. The multigraphed, printed or typewritten letter borne thereby may be either upon the folded over flap or on the body of the sheet, separately or may be common to both, so long as the particular feature of the utility afforded by the folded over part is attained, namely that special letter space may be obtained by a parent concern and furnished in stock form to its agents individualized for each. Thus any particular article reduced may be featured, together with a universal trade mark or advertisement, while on the front part of the flap, the particular agent's letter is printed, typewritten or multigraphed, whereby a large number of letters may be made up and adapted for only a particular use, as advertisement of the particular goods featured, but these will be available for a number of different agents without change of the picture display. Standard advertising is thus assured the principal, personal stationery and letter to the individual agent, or an application of both to the principal.

Having thus described my invention, I claim:

1. An illustrated sheet adapted to be used as a letter bearing printed matter upon one face thereof and being blank upon its opposite face, the said printed face having an upper letterhead portion and a display advertising portion there beneath, the advertising portion being adapted to be folded over upon itself, the original blank back face of the sheet thereby becoming a front face for the insertion of letter data and so positioned as to co-operate with the letterhead portion to form a complete letter.

2. An illustrated sheet adapted to be used as a letter bearing printed matter upon one face thereof and being blank upon its opposite back face, the said printed face being substantially rectangular and including an upper printed letterhead portion and a lower advertising portion, the advertising portion being adapted to be folded over upon itself substantially at the transverse middle line, and the original blank back face of the folded over portion thereby becoming a face for the insertion of letter data and so positioned as to co-operate with the upper letterhead portion to form a complete letter, and said letter thus concealing the advertising matter.

3. An illustrated sheet adapted to be used as a letter bearing printed matter upon one face thereof, the said printed face being substantially rectangular and including an upper printed letterhead portion and a lower advertising portion, the advertising portion being adapted to be folded upon itself substantially at the transverse middle line thus entirely concealing the advertising matter, and the original back face of the folded over lower portion being blank and thereby becoming a face for the insertion of letter data positioned to co-operate with the upper letterhead portion for forming a complete commercial letter in appearance, adapted to be folded up in the usual manner for enclosure in an envelop.

L. E. DELSON.
